INVENTORS:
WARD HARRISON,
JOHN H. WATERBURY,
BY *Alfred, Davis*
THEIR ATTORNEY.

UNITED STATES PATENT OFFICE.

WARD HARRISON AND JOHN H. WATERBURY, OF CLEVELAND, OHIO, ASSIGNEES TO
GENERAL ELECTRIC COMPANY, A CORPORATION OF NEW YORK.

LIGHTING UNIT.

Application filed September 6, 1922. Serial No. 586,415.

To all whom it may concern:

Be it known that we, WARD HARRISON and JOHN H. WATERBURY, citizens of the United States, residing at Cleveland, county of 5 Cuyahoga, State of Ohio, have invented certain new and useful Improvements in Lighting Units, of which the following is a specification.

Our invention relates to lighting fixtures 10 and more particularly to reflectors and shades for use in connection with electric lamps. Our invention is especially adapted for industrial lighting and comprises the combination of a reflector with a globe, the 15 reflector being ordinarily made of metal and the globe of glass. The object of our invention is to obtain an effective distribution of light in a downward direction so as to satisfactorily illuminate the work upon 20 which the operator is engaged and at the same time to provide an illumination for the ceiling and upper portion of the room so as to avoid the tunnel-like appearance which is characteristic of many of the present 25 industrial lighting installations. A further advantage is that the intensity of illumination of the visible light source is made very low. In other words, our invention gives a very much softer light than other 30 industrial units. A further advantage is that our device softens shadows and minimizes reflected glare from polished surfaces. A still further advantage is that our invention provides a very rugged unit since the 35 metal reflector, which is preferably used, serves to protect the glass globe from mechanical breakage and at the same time, the position of the reflector is such as to prevent glare.

40 In the drawing, we have shown a unit embodying our invention. Fig. 1 is an elevation of such a unit; Fig. 2 is a partial top plan view; and Fig. 3 is a fragmentary elevation of a modification.

45 As shown in the drawing, the incandescent lamp 10 is mounted in the usual socket 11. A holder 12 of a type which has been used and which comprises the spring fingers 13 and the cover cap 14 engages the upper lip 50 15 of the metal reflector 16. The said metal reflector is provided with a collar portion 17 which may be substantially vertical and

through which set screws 18 engage the lip 19 at the top of a glass globe 20 which is preferably integral and which incloses the 55 bowl portion of the incandescent lamp 10 above and below. The metal reflector 16 has a number of recesses 21 which are located in a substantially horizontally extending portion 22 and serve to allow light from the 60 globe 20 to pass upwardly to illuminate the upper portion of the room and the ceiling.

In Fig. 3 a modification is shown in which the separate holder 12 for the metal reflector 65 is dispensed with and the said reflector comprises a vertical portion 23, which serves as an attachment means to the support 24, the construction otherwise being substantially similar to that shown in Fig. 1. 70

What we claim as new and desire to secure by Letters Patent of the United States is:

1. In a lighting unit, the combination of a substantially vertically disposed incandescent lamp and a support therefor, a light diffusing globe substantially inclosing said lamp and an opaque reflector positioned over and partially inclosing said globe, said reflector being recessed to allow the transmission of a substantial portion of light in 75 substantially vertical directions through its upper portion, means for supporting said reflector and supporting means engaging said globe through said reflector. 80

2. In a lighting unit, the combination of 85 a light source, a globe inclosing the same, and a metal reflector positioned over said globe and extending downwardly there-around and substantially to the bottom thereof, and provided with means for allowing the transmission of a substantial portion of light through the upper portion thereof.

3. In a lighting unit, the combination of 90 a globe and an opaque reflector of larger diameter than said globe positioned over the same and extending downwardly there-around, said reflector having passages extending therethrough below the upper edge of said globe for allowing the transmission of a substantial portion of light through 95 said reflector from said globe. 100

4. In a lighting unit, the combination of a glass globe and a metal reflector of larger diameter than said globe, positioned over

the same and extending downwardly there-
around, said reflector being provided with
passages disposed below the upper edge of
said globe for allowing the transmission of a
substantial portion of light through said
reflector and means engaging said globe
through the portion of the said reflector

above said openings to support the said
globe.

In witness whereof, we have hereunto set 10
our hands this 1 day of Sept. 1922.

WARD HARRISON.
JOHN H. WATERBURY.

the same and extending downwardly there-around, said reflector being provided with passages disposed below the upper edge of said globe for allowing the transmission of a substantial portion of light through said reflector and means engaging said globe through the portion of the said reflector

above said openings to support the said globe.

In witness whereof, we have hereunto set our hands this 1 day of Sept. 1922.

WARD HARRISON.
JOHN H. WATERBURY.

DISCLAIMER

1,536,844.—*Ward Harrison and John H. Waterbury, Cleveland, Ohio. LIGHTING UNIT. Patent dated May 5, 1925. Disclaimer filed December 22, 1932, by the assignee, The Miller Company.*

Hereby enters this disclaimer to that part of claims 2, 3, and 4 which it does not choose to claim or hold by virtue of the patent or said assignment, to wit:

The combinations of elements set forth in claims 2, 3, and 4, respectively, of said Letters Patent No. 1,536,844, except when the globe recited in said combinations is a diffusing globe.
